UNITED STATES PATENT OFFICE.

FRANCIS T. MEYER, OF MONTCLAIR, NEW JERSEY, ASSIGNOR TO THE
MEYER-SNIFFEN COMPANY, LIMITED, OF NEW YORK, N. Y.

DESIGN FOR A PEDESTAL-URINAL.

SPECIFICATION forming part of Design No. 32,904, dated July 3, 1900.

Application filed April 9, 1900. Serial No. 12,251. Term of patent 14 years.

To all whom it may concern:

Be it known that I, FRANCIS T. MEYER, a citizen of the United States, residing at Montclair, county of Essex, and State of New Jersey, have invented and produced a certain new and original Design for Pedestal-Urinals, fully described and represented in the following specification and the accompanying drawing, forming a part of the same.

This invention relates to a new and original design for pedestal-urinals—that is to say, urinals in which the bowls or body portions of the urinals are supported when in position for use on suitable pedestals.

The invention consists in such a pedestal-urinal having a bowl or body portion of a peculiar shape or configuration, substantially as shown in the accompanying drawing, which

illustrates by a perspective view such a bowl or body portion mounted upon a suitable pedestal.

The leading feature of the design resides in the peculiar shape or configuration of the bowl or body portion, whereby the rear wall *a* thereof rises above the front wall *b*, substantially as shown.

What I claim is—

The design for a pedestal-urinal substantially as shown and described.

In testimony whereof I have hereunto set my hand in the presence of two subscribing witnesses.

FRANCIS T. MEYER.
